UNITED STATES PATENT OFFICE.

HENRY S. SMILEY, OF MEADVILLE, MISSOURI.

CULTIVATOR.

SPECIFICATION forming part of Letters Patent No. 269,732, dated December 26, 1882.

Application filed August 5, 1882. (No model.)

To all whom it may concern:

Be it known that I, HENRY S. SMILEY, of Meadville, in the county of Linn and State of Missouri, have invented certain new and useful Improvements in Cultivators; and I do hereby declare that the following is a full, clear, and exact description of the invention, which will enable others skilled in the art to which it appertains to make and use the same, reference being had to the accompanying drawings, which form a part of this specification.

This invention relates to cultivators for corn, &c.; and it consists in certain improvements in the construction and operation of the same.

In the drawings, Figure 1 is a plan view of twin cultivators embodying my improvements and attached to the axle of the sulky. Fig. 2 is a side view thereof, and Fig. 3 is a perspective detail view of one of the standards.

Referring to the drawings, A A designate the beams of the cultivators, each having a suitable handle, B, pivoted thereto at its lower end, C, and held in position by an inclined plate or brace, D, also pivoted at its lower end,

E, and provided with a series of perforations, F, through one of which and a perforation, G, in handle B a transverse holding-pin, H, is passed.

On beam A are arranged suitably-disposed standards I. The latter consist of a disk or plate, J, pivoted to the side of the beam by a pin or bolt, K, and provided on its opposite side with a segmental slot, L, in which works a set-screw, M, for regulating the position of the front end of the disk or plate.

N is a shank or standard projecting laterally from plate J, and provided near the outer

end with a slot, O, through which passes the spring cultivator-blade P, the position of the latter being regulated by a set-screw, Q, working at right angles to slot O.

R designates suitable brace-rods extending from the ends of the horizontal standard-stem N to the beam A.

To the front of beam A is swiveled, so as to be capable of only lateral movement, the usual clevis, S, comprising a U-shaped block, T, through the ends of which is passed a transverse pin, U, on which is pivoted a vertically-moving plate, V, which is adjusted on top the sulky-axle W. Under the latter is placed a separate clamping-plate, X, and plates V and X are caused to bind on the axle by bolts Y and nuts Z. In this manner the cultivators may be readily attached or detached, as desired.

The operation and advantages of my invention will be readily understood. It is simple, inexpensive, readily adjustable, and efficient.

I claim and desire to secure by Letters Patent—

The combination, with the beam, of the standard-plate pivoted thereto and having the integral lateral shank formed with a horizontal slot in its outer end, in which is adjustably secured the spring curved cultivator-blade, as set forth.

In testimony that I claim the foregoing as my own I have hereto affixed my signature in presence of two witnesses.

HENRY SANSON SMILEY.
